DESIGN.

J. CANNON.

FLAG OF THE ETHIOPIAN RACE.
APPLICATION FILED AUG. 21, 1920.

60,934.

Patented May 9, 1922.

Inventor.

James Cannon

UNITED STATES PATENT OFFICE.

JAMES CANNON, OF LONG BRANCH, NEW JERSEY.

DESIGN FOR A FLAG OF THE ETHIOPIAN RACE.

60,934.

Specification for Design.

Patented May 9, 1922.

Application filed August 21, 1920. Serial No. 405,176. Term of patent 14 years.

To all whom it may concern:

Be it known that I, JAMES CANNON, a citizen of the United States, residing at Long Branch, in the county of Monmouth and State of New Jersey, have invented a new, original, and ornamental Design for a Flag of the Ethiopian Race, of which the following is a specification, reference being had to the accompanying drawing, forming part thereof.

The figure of the drawing is a plan view of the flag embodying my new design.

I claim—

The ornamental design for a flag of the Ethiopian race, as shown.

JAMES CANNON.
